COMBINATION AUTOMOBILE AND AIRPLANE

Warder H. Skaggs, ½ Headquarters, 310th Bombardment
Wing, Medium, Schilling Air Force Base, Salina, Kans.

Filed July 27, 1960, Ser. No. 61,547

Term of patent 14 years

(Cl. D71—1)

FIG. 1

FIG. 2

FIG. 3

FIG. 9

FIG. 4

FIG. 5

FIG. 6

FIG. 7

FIG. 8

FIG. 1 is a front perspective view of a combination automobile and airplane embodying my new design, illustrated in position for flying;

FIG. 2 is a front elevation thereof, as shown in FIG. 1;

FIGS. 3 and 4 are top plan and side elevational views, respectively, of the combination as shown in FIG. 1;

FIG. 5 is a front perspective view of the combination automobile and airplane in position for use as an automobile;

FIG. 6 is a front elevation thereof as shown in FIG. 5;

FIGS. 7 and 8 are top plan and side elevational views, respectively, of the combination as shown in FIG. 5; and

FIG. 9 is a fragmentary longitudinal vertical section through the aft portion of the fuselage of the combination automobile and airplane.

The undisclosed side of the combination automobile and airplane is the same in appearance as the side shown. I claim:

The ornamental design for a combination automobile and airplane, substantially as shown and described.
